ADJUSTABLE MAGNETIC APPARATUS

Prescott D. Crout, Boston, Mass., assignor to Ray-theon Manufacturing Company, Newton, Mass., a corporation of Delaware

Application October 26, 1934, Serial No. 750,177

7 Claims. (Cl. 171—119)

This invention relates to an adjustable magnetic apparatus, and more particularly to such an apparatus in which the inductance thereof may be varied.

5 An object of this invention is to provide such an apparatus in which the current through said inductance is varied directly in accordance with the magnitude of motion of a controlling member.

Another object of the invention is to devise a 10 novel supporting structure for the movable magnetic member of such an apparatus.

A still further object is to provide a device of the kind indicated, which is simple and sturdy in construction and free from undesirable vibrations.

15 The foregoing and other objects of my invention will be best understood from the following exemplification thereof, reference being had to the accompanying drawings, wherein:

20 Fig. 1 is a side view of my novel apparatus with a portion of the top broken away to show the underlying structure;

Fig. 2 is a top view of the apparatus shown in Fig. 1 with certain portions broken away;

25 Fig. 3 is a cross-section of the upper portion of the structure taken along line 3—3 of Fig. 2; and

Fig. 4 is a side view of one of the laminations of the movable magnetic bar.

30 In my co-pending application, Serial No. 742,913, I have described and claimed a combined transformer and inductance control unit which is to be used in a welding machine. The present apparatus constitutes an improved form of the combined transformer and inductance control unit shown in said co-pending application.

35 In any adjustable magnetic apparatus in which the inductance is varied by varying an air gap, it is difficult to obtain a linear change of susceptibility in accordance with the magnitude of movement of the controlling member of the system. This is probably due to the fact that the susceptibility of the device, which is the reciprocal of the reactance, does not vary linearly

40 with the length of the air gap. When the air gap is small, a small change in its length will produce comparatively large changes in the susceptibility, while with a longer air gap, a smaller change in the length thereof will produce a much smaller change in susceptibility. In my present invention I have eliminated this difficulty by

45 moving a magnetic bar so as to produce a variable air gap by means of a controlling member in such a way as to produce a relatively small change in the air gap per unit distance of motion of said controlling member when said air gap is small, and an increasingly greater change in the air gap per unit distance of motion of said controlling member as the length of the air gap increases.

In the drawings the combined transformer and inductance control unit consists of a transformer 1 and a variable inductance 2. The various coils of the transformer 1 and the inductance 2 are preferably mounted on a combined core member 3 having three legs 4, 5 and 6 upon which the transformer coils are wound, and three additional legs 7, 8 and 9 upon which the three inductance coils 10, 11 and 12, respectively, are wound. The combined core member 3 has yokes 13 and 14 completing the magnetic path for the transformer, the yoke 14 forming also part of the magnetic path for the inductance coils 10, 11 and 12. The upper ends of the legs 7, 8 and 9 are formed with substantially flat pole faces and a movable magnetic bar 15 is disposed adjacent the outer ends of said pole faces. The magnetic core 3 and its associated coils are mounted within a frame 16. This frame has formed thereon a number of arms 17, whereby 20 the entire unit may be bolted in place into such a welding machine as shown in my co-pending application referred to above. The said core may be bolted in place on said frame 16 by means of a plurality of bolts 18. The coils 10, 11 and 12 25 are easily assembled on the legs 7, 8 and 9 by being slipped over the outer ends of these legs, and are retained in place by a plate 19 which may be formed of some suitable material, such as an insulating board. The plate 19 is retained in 30 place on the legs 7, 8 and 9 by means of bars 20 clamped on opposite sides of each leg 7, 8 and 9 by means of bolts 21.

Although I have described the above apparatus as consisting of both a transformer and an inductance unit, this invention is concerned primarily with the inductance unit itself. Thus this inductance unit could be an entirely separate member having a different number of legs and pole faces than that described above, and 40 likewise such inductance element may be useful in a cast number of instances aside from use in an arc welding machine.

In order that the inductance of the element 2 be variable, the magnetic bar 15 is movable with 45 respect to the pole faces of the legs 7, 8 and 9 in such a manner as to produce a variable air gap adjacent each of said pole faces. In order to support said magnetic bar 15, a frame 22 is bolted to the frame 16 at the upper end thereof 50 by means of a plurality of bolts 23. The frame 22 is provided with four cams 24, which cams form the supporting and guiding members for the magnetic bar 15. The magnetic bar 15 itself consists of a plurality of magnetic laminations 55 26 mounted within a sub-frame 25. One of these laminations 26 is shown in Fig. 4. As will be seen, the lamination is entirely imperforate and is provided with two projecting ears 27. In order to assemble the laminations within the sub- 60

frame 25, these laminations are merely slipped into said frame 25 with the ears 27 resting on the two ends of said sub-frame. In order that these laminations be tightly packed, a wedge 28 which 5 may be made of some suitable material, such as brass, may be inserted between the side of sub-frame 25 and the laminations 26. Since the sub-frame 25 consists merely of a hollow rectangular member, the sides thereof possess considerable 10 flexibility. In order that the laminations be still more firmly clamped within said sub-frame, said sub-frame is provided with upstanding ears 29 through which passes a bolt 30. By clamping the bolt 30 onto said ears 29, the sides of the 15 sub-frame 25 may be bowed in sufficiently to insure a firm clamping action on the sides of the laminations 26. It will be seen that these laminations are not provided with perforations for the purpose of bolting them into place on the 20 sub-frame. This results in an extremely simple form of lamination which is easily constructed and easily assembled. Due to the fact that the major force exerted on the laminations tends to move them in toward the pole faces of the legs 7, 25 8 and 9 and since the ears 27 on the laminations 26 oppose such motion, the resultant action is one which retains the laminations firmly in place in the desired position with respect to the sub-frame 25.

30 In order to support the magnetic bar 15 on the cams 24, the sub-frame 25 has formed integrally therewith the four sleeves 33 at the four corners thereof. Two shafts 34 are passed through the two end pairs of sleeves 33, and are 35 retained in place therein and prevented from turning by some suitable means, such as pins 35. The shafts 34 project beyond the outer ends of sleeves 33 so that the four rollers 36 may be slipped over the outer ends of the two shafts 34. 40 The four cams 24 engage the four rollers 36, respectively. In order to keep the rollers 36 in engagement with their respective cams 24 and thus maintain the magnetic bar 15 firmly in place, two tension springs 37 are connected to 45 the two ends of the sub-frame 25 by being hooked over projections 38 formed at the two ends of said sub-frame 25. The lower ends of the tension springs 37 are firmly retained in place on the frame 16 by being hooked onto projections 39 formed on said frame 16. These tension springs in addition to maintaining the rollers 36 on the cams 24 also prevent all backlash 50 and undesirable vibration of the magnetic bar 15 with respect to the rest of the structure. This 55 action is more fully described and claimed in my said copending application. In order that this function shall occur, the tension springs 37 are designed to exert sufficient pull on the magnetic bar 15 so that no chattering occurs between the 60 bar 15 and its associated structure.

It is difficult to support a rigid bar at four movable points inasmuch as each of said points should be in intimate contact with its respective supporting surface so that excessive backlash 65 and play is avoided and thus undesirable vibration and impact eliminated. In my device this difficulty has been avoided, and the four rollers 36 are always maintained in intimate contact with the four cams 24. Due to the fact that the 70 sub-frame 25 is a simple rectangular member and the laminations 26 are merely inserted into said sub-frame, the resultant structure has a considerable amount of torsional flexibility. Thus even if the cams 24 are not accurately 75 aligned, the sub-frame 25 will, under the action

of springs 37, twist so that each roller 36 is in intimate contact with its respective cam 24. The absence of any fastening member passing through the laminations 26 permits them to slide by each other to some degree, and thus the magnetic bar 15 participates accurately in the twisting of the sub-frame 25. In constructing the device, no special precautions need be taken to align the cams 24 or the rollers 36 accurately. When assembled the bar 15 will always be firmly supported at the four corners. The flexibility of the bar 15 and sub-frame 25 offers no disadvantage since when it is seated upon the cam 24 the rigidity of the frame 22 gives to the entire assembly the requisite stiffness. 15

In order further that the rollers 36 bear equally on the four cams 24, it is desirable for the force pulling the bar 15 toward the pole faces of the legs 7, 8 and 9 to act through the center of said bar. Thus the projections 38 are 20 located on the center line of bar 15, and the springs 37 exert their force along said center line. The magnetic force acting on the movable magnetic bar 15 also is exerted in such a way that the resultant force may be considered as 25 acting through the center of said magnetic bar. It is ordinarily very difficult to dispose the movable magnetic bar so that this result is obtained. In my device I have eliminated this difficulty by arranging the laminations 26 so that the central line 31 of the magnetic bar 15 is at all times nearer to the pole faces of the legs 7, 8 and 9 than the rest of said magnetic bar on either side of said central line. This is accomplished by shaping the two ends of the sub-frame 25 so that the 30 upper sides 32 thereof are shaped as indicated by the dotted line in Fig. 3. Thus merely by inserting identical laminations 26 into the sub-frame 25, the resultant magnetic bar takes the shape as shown in Fig. 3. Since the center of 35 the magnetic bar 15 is thus disposed so that it is nearest to the pole faces of the legs 7, 8 and 9, the resultant magnetic force exerted on said magnetic bar is accurately centered on said bar.

In order to produce the desired adjustment 40 and motion of the bar 15, a suitable controlling arrangement is provided therefor. Rotatably mounted on the bolt 30 is one end of a link 40. The other end of said link is rotatably connected to one end of a rod 41. The rod 41 is free to slide 50 through a sleeve 42 carried by a cross-bar 43 mounted on the upper side of the frame 22. Although the rod 41 is free to slide in said sleeve 42, it cannot turn therein. This is due to the fact that the link 40 connected to the end of rod 41 cannot turn, and thus prevents rod 41 from 55 turning. The opposite end of the rod 41 projects through said sleeve 42, and is threaded through a substantial length as indicated at 44. An actuating member 45 is provided with internal 60 threads which engage the external threads 44 on the rod 41. The outer end of the threaded portion 44 of the rod 41 is provided with a stop member 46 which is fastened in place on said rod 41 after the member 45 has been threaded into place. In addition to the springs 37, a small biasing spring 47 is provided which tends to move the reactor bar 15 to the left, as shown in Fig. 1, and likewise tends to move the link 40 and rod 41 in this same direction. Due to this biasing action, the actuating member 45 is biased so that it firmly engages the outer end of the sleeve 42. In order to rotate the actuating member 45, it is provided with a sprocket 48 70 75

which is engaged by a chain 49. Any suitable mechanism for moving the chain 49 may be used. Preferably the actuating mechanism may consist of the arrangement as shown in my said co-pending application. It will be seen that as the adjusting member 45 is rotated, the rod 41 will be moved to the left or right as shown in Fig. 1. As the rod 41 moves to the right, the magnetic bar 15 slides to the right, thus permitting the rollers 36 to ride down on the cams 24. The springs 37 insure the engagement of said rollers and cams as pointed out above. This action causes the air gap at the outer ends of the pole faces on legs 7, 8 and 9 to decrease, and thus increases the inductance of the coils 10, 11 and 12. As the rod 41 moves to the left, and magnetic bar 15 likewise is moved to the left, the rollers 36 are caused to ride up on the cams 24, thus increasing the air gap and decreasing the inductance of the coils 10, 11 and 12.

As will be seen from Fig. 1, the cams 24 are so formed that as the rod 41 moves to the left a definite distance when the magnetic bar 15 is in its lower position, a relatively small change in the relative position between the magnetic bar and its associated pole faces occurs. Thus a relatively small change in the length of the air gap is produced. Toward the upper position of the bar 15, however, if the rod 41 is moved to the left the same distance, a much greater change in the air gap is produced. Although the cams 24 can be designed so that the inductance of the coils 10, 11 and 12 varies in any desired relationship with respect to the movement of the actuating member 45, I prefer that these cams be formed in such a way that the susceptance of said coils changes substantially linearly with the angular distance through which the actuating member 45 is moved. Thus when the device is used in such an arc welding machine as described in my co-pending application, the current through the load will vary substantially linearly with the angular distance through which said actuating member is moved. I find that these conditions may be satisfied by circular cam surfaces.

It is to be understood that this invention is not limited to the particular details of the arrangement as described above as many equivalents will suggest themselves to those skilled in the art. For example, certain aspects of my invention may be useful in any magnetic apparatus in which an adjustable air gap is desired, even those in which but a single such air gap is provided. Various other changes and uses in and for the various novel parts of my invention will readily suggest themselves. It is accordingly desired that the appended claims be given a broad interpretation commensurate with the scope of the invention within the art.

60 What is claimed is:

1. In a magnetic apparatus, a magnetic core, means for setting up a magnetic flux in said core, said magnetic core having a variable air gap between a pole face and a movable magnetic bar, 65 said magnetic bar being supported at four movable points, a supporting surface at each of said points, and additional means for exerting on said magnetic bar a unidirectional force tending to move said bar toward said pole face and to seat 70 said bar firmly against said supporting surfaces, said magnetic bar having sufficient torsional flexibility to enable said magnetic bar to twist and compensate for variations in relative positions of said supporting surfaces, whereby said bar is al-

ways maintained firmly seated against said supporting surfaces.

2. In a magnetic apparatus, a magnetic core, means for setting up a magnetic flux in said core, said magnetic core having a variable air gap between a pole face and a movable magnetic bar, 5 said movable magnetic bar comprising a hollow frame member and a number of laminations of magnetic material inserted in said frame member, and abutments on said laminations engaging surfaces on said frame member and opposing motion of said laminations under action of said magnetic flux, whereby said laminations are retained in place in said frame member.

3. A magnetic bar comprising a hollow frame 15 member and a number of laminations of magnetic material inserted in said frame member, and abutments on said laminations engaging surfaces on said frame member and opposing motion of said laminations under action of a magnetic flux, 20 said frame member having side members and end members, said side members having sufficient flexibility to permit said laminations to be yieldably wedged into said frame member.

4. A magnetic bar comprising a hollow frame 25 member and a number of laminations of magnetic material inserted in said frame member, abutments on said laminations engaging surfaces on said frame member and opposing motion of said laminations under action of a magnetic flux, said 30 frame member having side members and end members, said side members having sufficient flexibility to permit said laminations to be yieldably wedged into said frame member, and means for clamping said side members against the sides 35 of said laminations.

5. In a magnetic apparatus, a magnetic core, means for setting up a magnetic flux in said core, said magnetic core having a variable air gap between a pole face and a movable magnetic bar, 40 the face of said magnetic bar facing said pole faces being disposed in more than one plane, the center line of said face being disposed closer to said pole faces than the rest of said face, whereby the center of the magnetic force exerted by said 45 magnetic flux is centered on said magnetic bar.

6. In a magnetic apparatus, a magnetic core, means for setting up a magnetic flux in said core, said magnetic core having a variable air gap between a pole face and a movable magnetic bar, 50 the face of said magnetic bar facing said pole faces being disposed in more than one plane, a predetermined portion of said face being disposed closer to said pole faces than the rest of said face, whereby the magnetic force exerted by said mag- 55 netic flux is centered on said predetermined portion.

7. In a magnetic apparatus, a magnetic core, means for setting up a magnetic flux in said core, said magnetic core having a variable air gap be- 60 tween a pole face and movable magnetic bar, means for supporting said magnetic bar at a plu- 65 rality of movable points on opposite sides of the center line of said magnetic bar, the face of said magnetic bar facing said pole faces being dis- 70 posed in more than one plane, the center line of said face being disposed closer to said pole faces than the rest of said face, whereby the center of the magnetic force exerted by said magnetic flux is centered on said magnetic bar, and the said 75 force is substantially equally divided between the supporting points on opposite sides of said center line.

PRISCOTT D. CROUT.
